ROTARY KNIFE FOR CUTTING YARN
ON QUILLSAlbert A. Hasler and Jacob Pfister, Hazleton, Pa.,
assignors to The Duplan Corporation, Hazleton,
Pa., a corporation of Delaware

Application June 28, 1945, Serial No. 602,106

6 Claims. (Cl. 242—19)

1

The present invention relates to means for severing the tail yarn during the initial portion of the winding of the yarn on a quill and particularly to the use of a rotary knife mounted on a spring pressed arm to effect such severing.

It is an object of the invention to provide a quill yarn severing device which will be automatically operable during the quill winding operation to sever the starting yarn and which is more effective and consistent in its operation than are the presently used devices of the same general character.

It is another object of the invention to provide such a device in which the rotary knife thereof is spring pressed against the quill to effect the severing operation.

It is a still further object of the invention to provide such a device which is simple and rugged of construction and simple and economical to manufacture.

Other objects and features of the invention will be apparent when the following description is considered in connection with the appended drawings, in which

Figure 1 is a perspective view of the working parts of the invention in the position which is assumed when a quill starting yarn is being severed;

Figure 2 is a fragmentary elevation partly in section showing the same operation as is illustrated in Figure 1;

Figure 3 is a view similar to Figure 2 but showing the position of the parts and particularly of the rotary knife when the starting yarn has been severed and the rotary knife has been raised from the quill;

Figure 4 is a fragmentary end view showing the relationships of the parts when they are in the position of Figure 3;

Figure 5 is a fragmentary end view similar to Figure 4 but showing the parts in the position of Figure 2;

Figure 6 is a plan view partly broken away showing the construction of the mounting means for the rotary knife;

Figure 7 is a cross sectional view of the device of Figure 6, the section being taken on the plane of the line 7—7 of Figure 6; and

Figure 8 is likewise a cross sectional view of the device of Figure 6, the section being taken on the plane of the line 8—8 of Figure 6.

In the prior construction of the same general type a hook-like knife has been utilized which, due to its small cutting area, became dulled with some rapidity and, furthermore, tended to remove the end of the yarn from the chuck in which

2

the quill is placed for the winding operation, thereby leaving a loose end to become entangled in the machine or, in some instances, to become wound on the quill so that the quill winding was improper.

In the present device we supply a rotary knife which is spring pressed against the heel of the quill, and which rotates with the quill, thereby presenting substantially different surfaces to the yarn for each cutting operation and cutting the yarn cleanly, close to the starting edge of the winding.

Referring now to the drawings in Figure 1 there is shown in perspective a quill 10 mounted in the usual manner in a chuck 11 which chuck is rotated by the usual drive means, not shown. The yarn 12 is fed through a yarn guide 13 and at the beginning of the winding operation the yarn guide 13 is so placed that the yarn is led across the mouth of the chuck 11 prior to the insertion of the quill 10 therein. Thus, when the quill is inserted the yarn lies in the chuck behind the quill as shown particularly in Figure 3 and is held until the time the winding is started by rotation of the chuck 11. The yarn guide 13 travels back and forth in small steps as the quill is wound and is at the same time fed constantly to the right as seen in Figures 1, 2 and 3 so that the resulting winding is of an ovate spheroidal form.

This progressive motion is transmitted to the yarn guide by means of the chain 14 which is fastened to the yarn guide support 15. Likewise fastened to the yarn guide support 15 is a cam member 16 which cooperates with and controls the motion of a pivot arm 17, this arm being pivoted on a rod 18 on which is also pivotally mounted an arm 20 which latter arm is spring pressed in a counterclockwise direction by any suitable means such as for instance a coil spring 41 which may be coiled about the rod 18 as shown in Figure 1. Thus, the arm 20 bears against a screw 21 mounted in an extension 22 of the arm 17, and thereby causes the bent over lug 19 of the arm 17 to bear against the cam 16. As will be clear from the drawing, adjustment of the screw 21 determines the normal position of the arm 17 and determines the extent of the cam surface which shall be utilized.

At its far end the arm 20 has formed thereon a U-shaped member 23 the two arms of which are drilled as indicated at 24 to provide mountings for a shaft 25 which is rotatable therein. Mounted at one end of the shaft 25 is a bracket member 26 (see Figures 6 through 8), carrying a pin 27 and having a set screw 28 whereby its

rotational position on the shaft may be adjusted. On the other end of the shaft 25 there is fixed an arm 30 which is provided at its far end with a ball bearing 31 in which there is mounted a shaft 32 having a threaded end and being provided with nuts 33 to hold it in place. Fixed to this shaft at the end opposite to the nuts 33 is the rotary knife 34, which is adapted to rotate with the shaft 32 in the bearing 31. Between the arms of the U-shaped members 23 a coil spring 35 surrounds the shaft 25 one end of the coil bearing against the pin 27 and the other end against the under surface of the base of the U-shaped member 23.

As is apparent from the foregoing description the spring 35 constantly urges the knife 34 in the direction of the quill 10 and when the arms 17 and 20 are rotated in a clockwise direction by the cam 16 the rotary knife 34 is pressed into a groove 36 in the heel of the quill 10. Thus, as the quill rotates the knife is driven with it, the pressure between the two being determined by the adjustment of the bracket 26 on the shaft 25 and the yarn is severed when the quill in its rotation causes the yarn to pass under the knife 34. Due to the knife form it will be clear that there is a very reduced tendency toward dulling of the blade since a large area of the knife is utilized and different portions presented to the yarn to be cut and that, furthermore, the knife has a true cutting movement with respect to the yarn and cuts the yarn where it is stretched across the groove 36.

The various stages of the operation are illustrated particularly in Figures 2 through 5. In Figures 2 and 5 the knife is shown in the position which it occupies when the cam 16 has progressed to a point where the bent over lug 19 rides on the highest portion of its surface and this time the knife is in contact with the quill and the cutting operation is about to be performed. In Figures 3 and 4 the cam is shown after it has passed beyond the range of the bent over lug 19 and in these figures the parts are shown in the position which they occupy before and after the cutting operation.

While we have described a preferred embodiment of our invention it will be understood that other forms and devices may be devised. Consequently we wish to be limited not by the foregoing description but solely by the appended claims.

What is claimed is:

1. In a device for severing the starting yarn during winding of a quill on an automatic machine, in combination, a rotary knife pivotally and resiliently mounted on one end of a pivotally mounted arm and adapted to cooperate with the quill, means for moving said arm toward and away from said quill, spring means for pressing the knife against the quill during the severing operation, and means for adjusting said spring means to thereby adjust the amount of pressure with which the said rotary knife bears against the quill.

2. In a device for severing the starting yarn during winding of a quill on an automatic machine, in combination, an arm pivotally mounted for movement toward and away from the quill, means for producing a timed movement of said arm toward and away from said quill, a U-shaped termination formed on said arm, a shaft supported in the arms of said U-shaped termination, a bracket adjustably fixed to said shaft at one end thereof, a pin extending from said bracket, a spring encompassing said shaft and having one

end bearing against said pin and the other against the base of said U-shaped termination, an arm fixedly mounted on said shaft and a knife rotatably mounted on the other end of said arm whereby said rotary knife is pressed against the quill by the rotation of said shaft under urge of said spring.

3. In a device for severing the starting yarn during winding of a quill on an automatic machine, in combination, an arm pivotally mounted for movement toward and away from the quill, means for timing the movement of said arm toward and away from said quill, a U-shaped termination formed on said arm, a shaft supported in the arms of said U-shaped termination, a bracket mounted on said shaft, a pin fixed in said bracket, means for adjusting the position of said bracket with respect to said shaft, spring means tending to rotate said shaft, and an arm mounted on said shaft, said arm carrying a rotatably mounted knife, the said adjustment of said bracket serving to adjust the spring pressure with which said knife is pressed against the quill.

4. In a device for severing the starting yarn during the winding of a quill on an automatic machine, in combination, an arm pivotally mounted for movement toward and away from the quill, means for timing the movement of said arm toward and away from said quill, a rotary knife pivotally mounted on the end of said arm, and means urging said rotary knife in a direction to make contact with the quill when said arm is at one extreme of its movement.

5. In a device for severing the starting yarn during the winding of a quill on an automatic machine, in combination, an arm pivotally mounted for movement toward and away from the quill, means for timing the movement of said arm toward and away from said quill, a rotary knife pivotally mounted on the end of said arm, spring means urging said rotary knife in a direction to make contact with the quill when said arm is at one extreme of its movement, and means for adjusting the said spring means to vary the pressure exerted by said rotary knife on said quill when said arm is in yarn-severing position.

6. In a device for severing the starting yarn during winding of the quill on an automatic winding machine, in combination, a rotary knife, means mounting said knife for movement toward and away from the quill, cam means for timing the movement of said mounting means, and spring means interposed between said rotary knife and said mounting means for constantly urging said rotary knife in the direction of said quill to thereby vary the pressure exerted upon the quill and the yarn to be severed when said mounting means is in its most forward position with respect to said quill.
